DESIGN FOR A MONEY BANK

James F. Lenhart, Paoli, Pa.

Application July 19, 1946, Serial No. 131,709

Term of patent 3½ years

(Cl. D34—11)

To all whom it may concern:

Be it known that I, James F. Lenhart, a citizen of the United States, resident of Paoli, in the county of Chester and Commonwealth of Pennsylvania, have invented a new, original, and ornamental Design for a Money Bank, of which the following is a specification, reference being had to the accompanying drawing, constituting a part thereof:

Fig. 1 is a front perspective view of the money bank, showing my new design; and

Fig. 2 is a top view thereof.

Fig. 3 is a side view on a reduced scale; and

Fig. 4 is a back view thereof on a reduced scale.

I claim:

The ornamental design for a money bank, substantially as shown.

JAMES F. LENHART,
